US00D956543S

(12) **United States Design Patent** (10) Patent No.: **US D956,543 S**
Li (45) Date of Patent: ** Jul. 5, 2022

(54) **LOCKING CONNECTOR**

(71) Applicant: **Wenjie Li**, Guangzhou (CN)

(72) Inventor: **Wenjie Li**, Guangzhou (CN)

(**) Term: **15 Years**

(21) Appl. No.: **29/755,972**

(22) Filed: **Oct. 23, 2020**

(30) **Foreign Application Priority Data**

Sep. 30, 2020 (CN) 202030594433.0

(51) LOC (13) Cl. **08-08**

(52) U.S. Cl.

USPC **D8/382**; D8/395

(58) **Field of Classification Search**

(57) **CLAIM**

The ornamental design for a locking connector, as shown and described.

DESCRIPTION

FIG. 1 is a front elevation view of a locking connector, showing my new design;

FIG. 2 is a rear elevation view thereof;

FIG. 3 is a right elevation view thereof;

FIG. 4 is a left elevation view thereof;

FIG. 5 is a top plan view thereof;

FIG. 6 is a bottom plan view thereof;

FIG. 7 is a right perspective view thereof;

FIG. 8 is a left perspective view thereof;

FIG. 9 is a top perspective view of the locking connector in its use environment; and,

FIG. 10 is a bottom perspective view of the locking connector in its use environment.

1 Claim, 10 Drawing Sheets
